UNITED STATES PATENT OFFICE.

LOUIS ZWEIG, OF BROOKLYN, NEW YORK, ASSIGNOR TO SUN RISE LAMP MFG. CO. INC.,
A CORPORATION OF NEW YORK.

DESIGN FOR A TABLE ORNAMENT OR ANALOGOUS ARTICLE.

Application filed November 23, 1927. Serial No. 24,255. Term of patent 3½ years.

To all whom it may concern:

Be it known that I, LOUIS ZWEIG, a citizen of the Republic of Austria, and a resident of the city of Brooklyn, county of Kings, and State of New York, have invented a new, original, and ornamental Design for a Table Ornament or Analogous Article, of which the following is a specification, reference being had to the accompanying drawing, forming a part hereof.

In these drawings:

table ornament or analogous article, the part shown in full line outline being ornamented in the same manner as the part more fully illustrated; and

I claim:

The ornamental design for a table ornament or analogous article substantially as shown and described.

LOUIS ZWEIG.
